GAS FILLED THYRATRON

Howard D. Doolittle, Stamford, Conn., assignor
to Machlett Laboratories, Incorporated, Spring-
dale, Conn., a corporation of Connecticut

Application June 15, 1951, Serial No. 231,772

35 Claims. (Cl. 315—62)

1

This invention relates to a novel gas filled thyatron for use at high power levels. More particularly this invention concerns a thyatron having a novel tube geometry which yields advantages in operating characteristics as well as structural strength.

Because of the limitations imposed by Paschen's Law on low pressure gas filled tubes, the spacings between grid and anode in such tubes must be carefully controlled. Assuming the use of any given gas at a fixed pressure, a minimum spacing below which the anode-grid spacing must be fixed in order to avoid breakdown between grid and anode is determined by the voltage therebetween. The higher the voltage the closer the grid-anode spacing must be. If the spacing between any point on the grid and the nearest point on the anode exceeds this minimum value, breakdown will occur between these points. It must also be remembered in adjusting spacings that breakdown tends to follow lines of force rather than straight lines or random paths. Furthermore, since field emission will occur if these elements are too close spaced, there is a lower as well as upper limit to the grid-anode spacing.

Most of the anodes used in the prior art have been necessarily almost completely surrounded by metallic grid potential shielding means which is also placed closely adjacent the anode at all points to prevent breakdown between grid and anode. Breakdown between grid and anode or between cathode and anode around the grid cylinder rather than through the perforations in high power thyatrons has also been prevented by enclosing the anode lead with a glass tube. Unfortunately, the necessity of so enclosing the anode within the grid and shielding structure has produced many difficulties. For instance, any conductive cooling of the anode has had to be accomplished through the anode lead which, at best, has been a long heavy rod. Furthermore, it has proved expedient to use structures of planar, rather than more complicated shapes, in order to avoid complication of the grid and shielding structures. Thus, if the tube's power capacity and anode radiating area were to be increased, it has been necessary to increase the tube diameter in order to accommodate a larger planar anode.

Accordingly it is an object of this invention to provide a thyatron suitable for use at high power levels having an anode which is thoroughly shielded from the cathode and close spaced to the grid. In order to accomplish my

2

object I employ a cylindrical anode in combination with a cylindrical active grid. This anode is supported by the vacuum envelope side walls or, in the alternative, forms part of the vacuum wall of my tube. It is advantageously located near the mid-point of the side wall which is composed primarily of glass or other insulation. The anode encircles the grid cylinder and is thereby shielded from the cathode which, in turn, is encircled by the grid potential cylinder. One end of this grid cylinder is sealed at one end of the tube to the envelope side walls. The other end of this grid cylinder, by virtue of spring fingers or other contacting means, slides upon the metallic terminating member of the envelope side walls at the opposite end of the tube. Thus, the only possible conduction path between the cathode and the anode is through the perforations in the active grid. Breakdown between grid and anode is avoided by keeping the effective length of the discharge path between the grid and anode shorter than the minimum breakdown spacing according to Paschen's Law. However, because the anode is not completely surrounded by the grid, and the grid cylinder, in fact, has points sufficiently far from the anode to permit breakdown, the insulation joining anode and grid is kept close spaced to the grid cylinder at points remote from the anode. Thus the lines of force will follow paths through the high permittivity material rather than through the gas-filled region. Breakdown cannot occur between grid and anode within the tube through this dielectric wall. Wall charges on the glass insulation also tend to provide a suitable field distribution to prevent breakdown from anode to grid. Outside of the tube breakdown cannot occur because the length of possible paths between grid potential members and anode potential members is well in excess of the maximum spacing for breakdown in the relatively high pressure air at atmospheric pressure.

It is another object of my invention to provide increased tube power capacity and to facilitate better heat disposal from the anode without materially increasing tube size. My cylindrical anode makes available a relatively large anode area. An increase in anode area may be accomplished as with the planar anode by increasing tube diameter, but it may also be accomplished without increase in tube diameter by increasing the axial length of the anode cylinder. The larger anode area permits more radiation of heat, and the anode location, adjacent the envelope, makes possible greater efficiency in radiation.

Also the location of the anode either in the vacuum wall or immediately adjacent to the vacuum wall makes possible a short, low heat-flow impedance thermal path for conductive cooling.

Limitations imposed on anodes for use in high power thyratrons have also imposed limitations upon the active grid structures (the perforated grid area) which may be employed with them. Overheating of the active grid has been common in prior art structures because of the high impedance thermal paths involved. Long, high heat-flow impedance thermal paths have been necessitated by the larger grid diameters employed. One problem resulting from thermal effects has been buckling of the grid which occurs because the active grid is heated and expands more than the surrounding support portion. This buckling produces a change in the grid-anode spacing which upsets tube characteristics considerably.

Accordingly it is an object of my invention to provide a grid structure in which the perforated active grid area is very short so that the thermal path to areas of high heat conductivity is decreased. My cylindrical grid arrangement permits this shortening because the same amount of active grid area as is presented by a large diameter planar member may be presented by my relatively narrow ring. Thus, it will be but a short distance from the middle of the active grid to the support thereof at either end.

It is another object of my invention to provide a grid which will not buckle and change the anode-grid spacing. My invention accomplishes this object by use of a grid cylinder one end of which is free to slide against the conductive end portion of the outer wall. Thus, as axial expansion of the grid occurs, due to heating, the spring fingers permit it to slide along this vacuum wall end member, thereby maintaining normal grid-anode spacing.

The cylindrical grid and anode structure is also advantageous from the standpoint of assembly. The requirement of enclosing prior art anodes within grid and shielding means makes it difficult to achieve accurate alignment of these elements. By my invention the anode may be placed in or adjacent to the outer vacuum wall and accurately aligned relative to the outer wall. Thereafter, the grid cylinder may be placed within the outer wall, accurately aligned with respect to the anode, and fixed in place to the outer wall.

The ease of alignment of the cylindrical tube parts also makes practical another novel feature of my invention. This feature consists of placing auxiliary electrodes between the anode and the grid. Auxiliary electrodes are advantageous in high power structures to perform the dual functions of dividing the voltage and shielding the anode from the grid. Voltage division is of advantage because it makes it possible to increase the grid-anode spacing for a tube of given voltage rating or to increase the voltage rating for the same grid-anode spacing. This is the case since, with the auxiliary electrodes in use, adjacent electrodes will have less voltage between them so that the minimum breakdown spacing according to Paschen's Law is increased.

A thyratron is rendered inoperable when its gas pressure is reduced below the level necessary to support conduction. Leakage, adsorption and absorption of the gas account for such reduction in pressure. Particularly significant is the amount of gas adsorbed by the glass or other in-

sulators during the operation of the tube. Glass has little tendency to adsorb the gas molecules as such, but it readily adsorbs gas ions.

It is therefore another object of my invention to reduce the amount of adsorption and absorption of the gas filling the tube. My invention accomplishes this end in at least three ways. It reduces the surface area of insulation in the tube; it places the insulation adjacent metallic surfaces so that it is inaccessible to ions; and it reduces the amount of ionization in the normally non-conducting region of the tube. The amount of insulation is reduced by the elimination of the conventional glass stem and the substitution of a tubular cathode sealed to the tubular end portion of the envelope side walls by a small ring of insulation. The metal grid cylinder shields the envelope side walls from ions and the small ring of insulation between cathode and grid is placed close to metal so that little space is left for occupancy by ions. The tubular cathode and terminal structure has a sufficiently low inductance that the cathode surge voltage produced by current pulses in cathode lead ionizes relatively few molecules of gas despite the high rate of change of current involved. Thus only a small amount of the gas in the grid-cathode region adjacent the insulation is subject to adsorption.

The rate at which firing may be repeated is a very important factor in many thyratron uses. The repetition rate may be and is often quite high for small power thyratrons, but, as power is increased, the possible repetition rate decreases. This is so because the heavy current drawn during the start of the firing heats the anode more than the current during the remainder of the firing period which latter period may be much longer. Thus, as heat dissipation capabilities are increased, such as they are by my invention, the repetition rate may be increased. However, even though anode dissipation is adequate, the repetition rate is limited by another factor. Before the grid can regain control after firing, the region between cathode and grid must be cleared of ions. Thus the faster the ions are removed after firing the faster the repetition rate.

Accordingly, it is another object of my invention to increase the possible repetition rate in thyratrons by the more rapid neutralization of ions. My invention accomplishes this end by placing grid or cathode potential metallic vanes in the space between cathode and grid. It is most important to place these vanes in the region adjacent the active grid where ionization is extensive. However, the vanes may be used to advantage in other portions of the tube also. The location and shape of the vanes is governed by their purpose, namely to cut down the distance that ions travel to a neutralizing surface, thereby cutting down on the deionization time.

Whereas use of the deionizing vanes minimizes the amount of necessary baffling in thyratrons, it is still often desirable to employ baffling for greater grid control. Baffling in the prior art has had the undesirable effect of restricting the conduction currents in the tube to limited paths. This is so because the conduction streams tend to confine themselves to paths of approximately equal length. Thus a circular baffle placed directly in front of a planar active grid has confined conduction currents to those terminating in a ring on the anode.

Accordingly, it is another object of my invention to better distribute the overall loading of the

anode. I accomplish this object by arranging baffle means to cover individual perforations which baffles terminate at equal distances from their respective perforations so that the conduction path between cathode and anode through any perforation is essentially the same length. That is, I use narrow baffles which adequately cover the perforations but not large areas of the imperforate regions of the active grid.

Although the features of my invention are conveniently used to advantage with my novel cylindrical tube geometry, they may also be applied in various prior art thyratron structures. Reference to the following drawings will illustrate additional advantages and give a better understanding of my invention:

Fig. 1 shows in section a preferred form of my novel thyratron structure.

Fig. 2 is a cross section view of the same tube taken at section 2-2 of Fig. 1.

Fig. 3 is a cross sectional view of the same tube taken at section 3-3 of Fig. 1.

Fig. 4 shows in partial section an alternative form of my novel thyratron which employs a voltage dividing anode for use in tubes to be operated at higher voltage.

Fig. 5 shows in section an alternative arrangement of deionization vanes in combination with the active grid which may be substituted for the baffle-vane structure of Fig. 2.

Fig. 6 shows in section still another alternative form of deionization vanes which may be substituted for the baffle-vane region shown in Fig. 2.

Fig. 7 shows a single vane of the type employed in the Fig. 6 construction.

Fig. 8 shows a view of the active grid of Fig. 6 without the vanes affixed and with a segment broken away to show how the vanes are fixed to the grid structure.

Fig. 9 shows in partial section a planar type of thyratron employing some of my novel features including individual baffle means.

Referring to Fig. 1 the tube illustrated has a tubular anode 10 which is supported by means of an annular, radially outward extending flange member 11 to which it is brazed or otherwise permanently affixed. This bange in addition to providing support for the anode offers a large area, low impedance heat flow path from the anode to the outside of the tube envelope. The flange member is advantageously affixed to the tube envelope side walls by sandwiching it between the radial portions of annular bracket members 12 and 13. These bracket members have tubular portions coaxial with the anode which extend in opposite directions from the flange 11, thus enabling them to be affixed to the tubular glass side wall members 14 and 15. It is also possible to make the anode part of the vacuum wall of the tube, but the construction described makes it possible to employ an anode and flange having better conducting qualities and wall portions having a coefficient of expansion close to that of glass in order to obtain better seals.

The active grid member 17 consists of a ring lying coaxially within the tubular anode. This ring may be very short in axial length and still present the same active grid area as is presented by planar prior art structures. Thus the heat flow impedance to the edges of the grid is materially decreased over thyratron grid structures of the prior art. Perforations in the grid are advantageously a single row of parallel elongated slots. These perforations are superior to perforations in prior art grids in that they are

equidistant from the cathode. Thus conduction currents will not tend to favor certain perforations and ignore others since the path length from cathode to anode is the same through every grid slot. Furthermore, the elongation of the perforations prevents point bombardment of the anode by positive ions during inverse voltage periods. Instead, the destructive effect of the bombarding ions will be distributed along a line and hence diminished at any one point.

As in thyratrons of the prior art, the active grid of my tube is affixed to a grid cylinder (members 19 and 20). However in this instance the active grid 17 is cylindrical itself and actually forms a segment of the grid cylinder. As in the prior art it is the function of the grid cylinder to act as a shielding means which prevents discharge between the cathode and the anode other than through the perforations of the active grid.

My grid cylinder is made more effective than prior art structures in preventing such improper breakdown in view of the fact that it is intended to be used at high power levels. Such breakdown is prevented by terminating both ends of the grid cylinder at the vacuum envelope. However, since it is a purpose of my invention to prevent buckling of the active grid, both ends of the grid cylinder cannot be fixed to the vacuum wall. Thus by my invention one end of the grid cylinder, an edge of member 20, is affixed to the envelope side walls. In order to permit the use of high conductivity material as grid cylinder member 20, a tubular collar 21 of metal having good properties for glass to metal joints may be used to seal

an edge of member 20 to side wall insulator 15. The other end of the grid cylinder, an edge of member 19, must be fixed in place. In order to insure its freedom to move as well as a constant contact with the envelope side walls, resilient contact means, such as spring fingers 22, is affixed to member 19. To avoid the necessity of its contacting the insulator 14, a tubular metallic extension 23 to the envelope side walls is sealed to insulator 14. The contact between the resilient means 22 and the tubular extension 23 permits the use of member 23 as a grid terminal.

The active grid 17 may be fabricated as an integral part of a one piece grid cylinder. However, it is often desirable to use different materials for the various segments of the grid cylinder. For instance, it is easier to perforate a small strip than a large sheet or cylinder. Furthermore, by using a separate tubular member for grid cylinder segment 20 it is possible to provide a low impedance heat flow path to the outside of the envelope. It will be noted in this connection that, by placing the end wall 24 immediately adjacent the active grid 17, the whole inner surface of tubular member 20 as well as the end wall 24 is available for convective cooling.

The cylindrical geometry of this preferred tube structure lends itself to accuracy in positioning and alignment. In assembly, for instance, the anode may be easily aligned for accurate sealing to the side wall insulators. Likewise, the assembled grid cylinder may be sealed to collar 21 and then accurately centered with respect to the anode before sealing the collar 21 to the insulator 15. The anode may be made long enough in the axial dimension so that a portion of it always opposes the active grid which is free to change its axial position to compensate for differential expansion. In this connection, it is advantageous to make the grid cylinder, including the active grid, of essentially constant diameter so

that its axial shifts in position will never result in collision with the anode or side walls.

The problem of collision of some portion of the grid cylinder and the anode or the envelope side walls during relative expansion arises because of the necessity for keeping the insulators close spaced to the grid cylinder. Since the anode is not completely surrounded by grid potential members as it has been in prior art structures, breakdown between grid and anode would seem to be more probable. The minimum spacing between anode and cathode which will permit breakdown for the particular pressure of the particular gas used according to Paschen's Law must not be exceeded. However, breakdown is avoided in my structure by the judicious positioning of insulators 14 and 15 which are so shaped that their spacing from the grid throughout most of their respective lengths is in the order of the grid-anode spacing at its closest point. Thus the lines of force between the anode and portions of the grid remote from the anode pass through the low permitivity insulation which acts as a barrier to prevent breakdown along such lines. In addition, the accumulation of positive wall charges on insulators 14 and 15 cause lines of force from the grid to go directly to the insulators rather than curving toward the anode.

It is usually of advantage to use oxide coated cathodes in thyratrons in order to obtain high electron emission. The location of the active cathode area in the thyratron may be considerably varied. I employ a tubular cathode 27 in my thyratron which lies within the grid cylinder extension 19, well removed from the active grid area. Either the outer or inner surface of the cathode tube 27 may be coated with oxide emitter. However, it seems preferable to place the emitter on the inside of the cathode tube so that the conduction current is partially diverted by lateral baffle plate or cap 28 which may be supported on tab supports 29 which are joined to the cathode. A tab 30 extends from the center of the baffle plate 28 toward the cathode 27. To the end of tab 30 is affixed high inductance heater coil 31 which lies within the cathode cylinder in a position essentially coaxial with the cathode. The heater is terminated in axial conductor 32. Conductor 32 passes through an insulating washer 33 which is supported by annular plate 34 which is in turn affixed to the cathode cylinder. The heater lead 32 may be attached to a rod lead 35 which lies on the tube axis coaxially within cathode cylinder 27. This rod may be sealed to thimblelike member 36 which is composed of material which in turn may be sealed to annular insulator 37. Insulator 37 thus forms the major portion of the vacuum wall between cathode cylinder 27 and heater lead 35. The cathode cylinder 27 and the heater lead 35 are thus brought out coaxial with grid terminal 23 and extend to any desired length, in order to make convenient connections with its circuitry.

The tubular member 27 is continuous from the outside of the vacuum wall to the cathode surface. This large diameter tube effectively forms a low inductance lead which replaces the high inductance leads of the prior art. Thus, despite the high rate of change of current which occurs, the surge voltage pulse in the cathode lead which is a product of the lead inductance and current rate of change, is materially reduced over that in prior art structures. This voltage reduction tends to reduce the opportunity for untimely

breakdown, but, even more important it tends to decrease the amount of ionization near insulation produced by the voltage pulse. Furthermore, it prevents damage to the tube and minimizes disturbances in the related circuitry.

Pulse current in the heater is undesirable. Even a small increase in heater current will greatly increase the temperature of the filament and hence its decomposition rate, consequently materially shortening filament life. Thus my filament is preferably a high inductance coil connected at one end to the low inductance cathode and at its other end to a simple rod or wire whose inductance is relatively high compared with the cathode lead. This heater lead is advantageously located coaxially within the cathode terminal with an insulating member forming part of the vacuum envelope of the tube sealed therebetween. Thus it is difficult for high current pulses to get into the heater and reduce tube life.

The fact that both the cathode cylinder 27 and the members 19 and 23 making up the adjacent grid lead are tubular and of low inductance minimizes the amount of ionization which can take place in the region between cathode and grid. In fact due to Paschen's Law any discharge will tend to take place between members 19 and 27 where the spacing is great, i. e., away from glass. However, even if ions drift into the region of the glass the use of tubular leads makes it possible to use a relatively small amount of insulation in a ring seal 23 between the grid potential side wall member 23 and the cathode tube 27 rather than the large amount of glass conventional in stem presses, so that there will be less insulation to adsorb or absorb ions formed in the region adjacent the insulators. My structure avoids the adsorption or absorption of gas ions by the insulation not only by reducing the amount of insulation used but also by placing the insulation in such locations that the number of stray ions able to reach it is greatly reduced. A pair of tubular metallic sleeves 40 and 41 sealed to opposite edges of the insulating ring 39 complete the sealing means between the grid potential side wall member 23 and the cathode tube 27. These sleeves are made of such shape that the ring insulator 39 is close spaced at all points to the grid potential member 23. In addition sleeve 40 has a portion adjacent that edge sealed to insulator 39 which is also close spaced to member 23. This spacing should be as close as possible without defeating the purpose of the configuration by permitting breakdown. Thus it is difficult for ions to get into the small space between insulator 39 and member 23. Furthermore many ions drifting toward this region will contact sleeve 40 or member 23 in the process and be neutralized.

The grid leads, like the cathode leads are advantageously tubular in shape and consequently of low inductance. In my structure connection to the tubular grid structure may be made at both ends of the tube. The low inductance of the grid leads is of great advantage because it offers greater control of the tube through appropriate circuitry. For instance it is advantageous to limit by the use of external impedance the feedback into the triggering circuit. This feedback is produced by the high grid voltage spike in the grid which appears due to the conductive coupling between grid and anode during initiation of the discharge. The voltage spike may be kept out of the trigger circuit easily in

my tube because any amount or type of impedance may be placed between the grid and the trigger circuit so that a minimum disturbance for any set of operating conditions may be achieved, and/or an optimum value of impedance may be selected to make the build up of current between cathode and anode occur under the most favorable trigger conditions.

The use of oxide coated cathodes is highly desirable in thyratrons because of the high emission possible with this type of emitter. Use of the oxide coating, however, involves the problem of converting carbonates to oxides. This process must be carried on under vacuum conditions to assure the formation of oxides rather than other compounds. During the conversion large quantities of gas are evolved. These gases are partially adsorbed and absorbed by the grid and the anode with the result that these structures are very difficult to completely outgas later.

My cathode assembly makes it possible to convert the carbonates to oxides before placing the assembly in the vacuum envelope with other tube elements. My cathode assembly including the sealing means consisting of insulator 39 and sleeves 40 and 41 may be conveniently sealed into a vacuum envelope without other elements, and there the carbonates converted to oxides. This may be conveniently done by sealing sleeve 41 to a tubular member similar to member 23 at one end of the temporary envelope using a low melting point solder or by gasketry. After conversion, the seal may be melted and the cathode assembly sealed in place to member 23.

Fig. 2 shows a cross section of Fig. 1 in the active grid region, wherein the anode terminal flange 12, the anode 10 and the grid 17 are shown in section. Close spaced to and coaxial with the grid is baffle ring 43. To this baffle ring are affixed a plurality of inwardly extending metallic deionization vanes 44 which may be of varied length and whose primary object is to present a large amount of grid potential area in the region adjacent the active grid. The function of these vanes is to quickly capture positive ions when conduction current is to be stopped. The preponderance of the ions in the tube accumulate in this region. The neutralization of such ions necessary for the stoppage of conduction is thus accomplished more rapidly by virtue of the large area at grid potential offered by the vanes and the short paths the ions must take to reach these vanes.

Deionization vanes of this sort may be used in other portions of the tube and are conveniently affixed to the grid cylinder or other suitable grid or cathode potential surface such as baffles. For instance, it is often expedient to interpose a number of vanes in the region intermediate the cathode and the grid. It is common to employ a lateral baffle member 45 at whose center is a hole. Vanes affixed to this baffle structure may vary in length so that they extend into the region of the hole. Fig. 3 illustrates how this may be done where vanes 46 are mounted on both sides of the baffle plate and extend into the hole. This section also shows annular bracket 13, anode 10 and grid cylinder 19.

The operation of this thyratron is similar to others well known in the art. Under normal operating conditions, a high positive potential is applied to the anode and the cathode is maintained at ground. The grid potential is varied; when negative or cathode potential (or possibly slightly positive), the grid prevents the flow of

conduction current within the tube. It is normally a positive potential appearing on the grid which initiates conduction in the tube. Conduction currents in such a gas filled tube take devious paths, e. g., in this instance from the cathode cylinder 27, around baffle plate 28, through the hole in baffle plate 45, around baffle ring 43, through slots 18 in the grid 17 to the anode 10. The more devious the path, the higher the pulse required to fire the tube, i. e., the greater the control of the grid over tube firing.

Fig. 4 illustrates a tube which is quite similar to the tube of Fig. 1 but which differs in that it may be used more readily at higher voltage levels.

15 Like the tube of Fig. 1 this tube has an anode 10' supported by a flange 11' which is sandwiched between annular members 12' and 13'. Likewise annular members 12' and 13' are affixed to tubular insulators 14' and 15' axially located on both 20 sides of the anode and forming portions of the vacuum envelope. Insulator 15' is essentially the same as 15 in Fig. 1. However, instead of being affixed to a member corresponding to member 21, it is affixed to an annular bracket member 25 48 which is similar to member 13'. Bracket 48 is opposed by annular bracket member 49 similar to member 12'. Between the annular brackets is sandwiched radial support member 50 which is similar to support member 11. Radial support member 50 supports tubular auxiliary electrode 51 which extends from the support 50 to an axial level beyond the remote edge of the anode passing between the anode 10' and the grid 17'. It is advantageously perforated with 30 elongated slots similar to those in the grid but preferably out of alignment with those of the grid so that conduction currents must take a longer, more devious path to reach the anode and so that positive ions will have more difficulty 35 bombarding the anode during inverse voltage periods. Dielectric side wall member 54 is affixed to annular bracket 49 at one edge and to a metallic terminating member 21' at its other edge. The length and shape of insulation between electrodes 45 may be varied, of course, in order to provide for the particular conditions under which a particular tube is to be used.

The spacing between grid and anode at high voltages is extremely critical. This spacing must be fixed within a very narrow range. If it is too close, field emission can occur. If it is too wide, breakdown will occur according to Paschen's Law. As voltage is increased this range grows smaller. Since use of an auxiliary electrode en-

ables wider spacing of adjacent electrodes and/or reduces the potential difference between adjacent electrodes, the problem of field emission ceases to be serious. Likewise, since the path length necessary for breakdown between grid and anode decreases with increased voltage, use of the auxiliary electrode at an intermediate potential affords shielding of the anode from the grid and actually increases the minimum breakdown spacing between the elements.

65 To divide the voltage, a resistance divider of high impedance may be located outside of the tube between the anode and cathode with tap connection to the auxiliary electrode, positioned to maintain any desired potential on the auxiliary electrode. Optimum conditions would obtain where spacings between grid, auxiliary electrode and anode were equal and the auxiliary electrode was held at a potential midway between that of anode and grid. According to Paschen's 70 Law a tube with the auxiliary electrode in non-

conducting state would withstand about double the voltage obtainable for the same conditions, including the same grid-anode spacing, in a tube without the auxiliary electrode.

The shielding function of the auxiliary electrode is accomplished simply by extending the auxiliary electrode beyond that edge of the anode cylinder remote from the terminal of the auxiliary electrode so that no lines of force extend directly between grid and anode. In order to reduce electrical stresses between the edge of this element and the grid and in order to better shield the anode 10' the edge of this auxiliary electrode 52 is rounded or curved outward.

Alignment of the tubular auxiliary electrode is relatively simple since the voltage dividing anode may be first aligned with the anode and then fixed in place to the outer vacuum wall in the same manner employed with the anode. Thereafter the grid slots may be aligned with, or placed in opposition to, those in the voltage dividing anode prior to fixing the grid in place. Any number of auxiliary electrodes concentrically arranged may be employed. While many auxiliary electrodes would produce a more complicated assembly problem, it would also afford a means of greatly increasing anode voltage and hence the power capacities of the tube. In addition to the problem of alignment of perforations, a multi-auxiliary-electrode structure presents a problem in shielding. Shielding is satisfactory as long as each auxiliary electrode shields the surrounding electrodes from the surrounded electrodes. A voltage dividing electrode may be employed with a planar type anode, but the complication in its positioning and support would probably make such use impractical.

The active grid 17' of the Fig. 4 tube forms a segment of the grid cylinder continued by grid cylinder 19' which terminates in spring fingers 22'. Spring fingers 22' contact tubular outer wall termination member 23' which is sealed to dielectric wall 14'. Tubular grid terminal 20', also a continuation of the grid cylinder, is sealed to side-wall termination member 21' at one end and to end wall 24' at its other end. The active grid 17' has the same outer diameter as grid cylinder extension 20' and has one edge affixed to the wall 24'. Ring baffle 43' lies within and is close spaced to the grid slots 18' and may be affixed to wall 24'.

The cathode cylinder 27' is supported by tubular member 40' joined to tubular member 41' by glass ring-seal 39'. Tubular member 41' is sealed to grid terminal 21' thus completing the vacuum wall. The internal assembly of the cathode is advantageously the same as that of Fig. 1. Atop the cathode is mounted baffle plate 28'. Between the baffle plate and the grid is located baffle plate 45' affixed to the grid cylinder and having a hole at its center.

The structure of Fig. 4 may also have deionization vanes like those of Fig. 1. In the case of both types of tubes, however, other types of deionization vanes may prove desirable in many instances. For instance, those shown in Fig. 5 provide a tortuous path from any point within the grid ring to the grid slots. When this type of vane structure is used a ring type baffle plate such as 43 or 43' may not be used. The convolutions in the vanes 56 and 57, which differ in length, minimize the number of ions which can take a straight path from any point within the grid ring to the grid perforation and thence through to the anode during the inverse voltage

period. Further protection against ions is rendered by the small, individual baffles 58 which lie in front of the grid slots and each of which is affixed to the grid adjacent a perforation. Said baffle means effectively replace the cylindrical baffle 43 of Fig. 1 in adding to the grid's control.

The structure of Fig. 5 is excellent for many uses but in other instances the structure of Fig. 6 might be preferred. In the Fig. 6 construction vanes 59 of the shape illustrated in Fig. 7 are arranged within the grid ring and affixed directly thereto as in the case of the Fig. 5 structure. Fig. 8 shows how the vanes shown in Figs. 6 and 7 might fit into a grid ring by illustrating the active grid ring alone showing the slots for receiving the vanes. The vanes extend beneath the slots so that they lie between the active grid and the cathode region. Thus it is impossible for an electron to come directly up from the region between the cathode and the grid. Likewise, it is difficult for ions not extremely close to the grid slots to approach these slots and pass therethrough. In fact, unless they are extremely close to the slots, in order to pass through the grid slots, ions will have to take curved paths, contrary to their tendencies. The fact that these vanes are affixed to the active grid adjacent each perforation, so that they partially block the perforation, makes them excellent for baffling purposes.

Because of an overlapping of function, I wish to more specifically define the nature and purpose of my deionization vanes as opposed to baffles. It is the primary purpose of these deionization vanes to present as much grid or cathode potential area as possible throughout the region of heavy ionization in order to shorten the path which the ions must take to be neutralized. By doing this it is possible to decrease the deionization time and increase the repetition rate of firing the tube. Because they tend to partially block conduction paths, the deionization vanes have some of the characteristics and act to some extent like baffles in that they increase the amount of grid control. Thus when deionization vanes are used other baffling may be largely omitted lest the grids have too much control so that too much voltage must be applied to trigger the tube.

By the same token my invention introduces a novel means of baffling in thyratrons. My invention provides individual baffling for each perforation in the grid or at least presents the same amount and kind of baffling for each perforation. That is to say, unlike the prior art baffles which covered a whole active grid area, my baffles cover only the minimum area necessary for control, i. e., the perforations and adjacent regions. Thus conduction streams through different perforations do not have to travel different distances between cathode and anode around a single baffle covering all perforations. The path length between cathode and anode through any perforation is essentially the same. My invention achieves this end by the use of baffling means over or in front of each perforation in the active grid which extends the same distance beyond each perforation in the region where conduction currents pass. I achieve this end by several means. In the Fig. 1 type tube a concentric tubular baffle as shown may be used. Where the more complicated deionization vanes are used, however, it is necessary to mount individual baffles adjacent each perforation as in

the Fig. 5 construction or use a portion of the deionization vanes to the same end as in Fig. 6. Thus it is possible that deionization vanes may serve as baffles just as baffles always serve as deionization means. In this connection it will be noted that my baffle means are particularly valuable in reducing bombardment of the anode by positive ions during inverse voltage periods.

Many of the features of my invention are equally applicable to planar anode thyratrons as they are to my novel cylindrical geometry. To be more specific the cathode structure, the deionization vanes and the baffle means may all be employed in planar as well as cylindrical geometry thyratrons. Fig. 9 illustrates how my novel cathode may be used in such a tube and in addition illustrates an adaptation of my novel baffling means. The planar thyratron of Fig. 9 is advantageously operated with the grid grounded. This thyratron employs baffles 61 and 62 having portions extending perpendicular to the plane of the grid and portions affixed thereto extending parallel to the grid and overlying the perforation. These members are made to overlap one another so that conduction currents will have to take a devious path in order to reach the anode. The close proximity of vane 62 to the grid slot reduces the ions which pass through the grid slot and bombard the anode during the inverse voltage period. However, as illustrated a large pulse would be required to trigger the tube. Omission of either baffle 61 or 62 would reduce the amount of trigger required.

As mentioned, this tube contains the same general type of tubular cathode as the Fig. 1 structure with a cathode cylinder 27" topped by baffle plate 28". However, the tube envelope in this instance is unique in that it is also the grid cylinder 19" which may extend the full length of the tube. The cathode is affixed to this cylinder by means of tubular sleeves 40" and 41" sealed to ring seal 39". Thus cleanup of the gas may be avoided by positioning insulator 39" close to grid 19". The rest of the structure differs from the cylindrical variation. The anode 64 is planar and has an axial rod support-conductor 65 affixed to it. Insulator 66 between anode lead 65 and tubular member 67, which is sealed to the end of grid cylinder 19", forms the end-wall vacuum closure. The active grid in this instance is a planar member 68 which has perforations 69 which are baffled as aforementioned by vanes 61 and 62. The active grid is sealed in place to the grid cylinder at a spacing which does not exceed the minimum value for breakdown between grid and anode under the particular conditions existent in that tube. The inactive side of the anode is close spaced from shielding member 70 which is terminated in a tubular flange 70a which fits around tubular glass flange 66a which, in turn, extends from insulator end-closure 66.

In essence this tube operates essentially as the tubes shown in Figs. 1 and 4. It is subject to many of the disadvantages encountered in planar tubes above enumerated, such as difficulties with anode dissipation, problems of grid buckling, etc. However, with such a low inductance grid lead, it is advantageous to ground the grid and fire the tube by a negative trigger on the cathode. Such operation eliminates the high voltage grid spike due to the conductive coupling between grid and anode during the initiation of the discharge with its accompanying problem of feedback into the trigger circuit. In addition, less baffling between anode and cathode may normally be used because of the low impedance between grid and the nega-

tive return lead of the plate power supply. This amounts to improved efficiency and low anode dissipation.

I claim:

1. An electron tube comprising a vacuum envelope filled with low pressure gas and having therein an anode, an emitting cathode, a grid wall between the anode and the cathode which has perforations therein opposing the anode and the edges of which terminate at portions of the vacuum envelope, baffle means so positioned between cathode and grid and close to the grid perforations that the path lengths between cathode and anode through each grid perforation are substantially equal, metallic deionization vanes affixed to portions of the grid, and auxiliary electrodes between the grid and the anode having perforations therethrough.

2. An electron tube comprising a vacuum envelope filled with low pressure gas and having therein a cylindrical anode, an emitting cathode, a cylindrical grid wall between the anode and the cathode which has perforations therein opposing the anode and the edges of which terminate at portions of the vacuum envelope, baffle means so positioned between cathode and grid and close to the grid perforations that the path lengths between cathode and anode through each grid perforation are substantially equal, metallic deionization vanes affixed to portions of the grid and cathode, and cylindrical auxiliary electrodes between the grid and the anode having perforations therethrough.

3. A coaxial tube structure comprising a vacuum envelope filled with low pressure gas and having therein a cylindrical anode, an integral cathode assembly consisting of a tubular cathode to which emitter is applied and a high inductance filamentary heater lying coaxially within the tubular cathode, a cylindrical grid wall between the anode and the cathode which has perforations therein opposing the anode and the edges of which terminate at portions of the vacuum envelope, baffle means so positioned between cathode and grid and close to the grid perforations that the path lengths between cathode and anode through each grid perforation are substantially equal, metallic deionization vanes affixed to portions of the grid and cathode and extending into the space between the grid and cathode, and cylindrical auxiliary electrodes between the grid and the anode shielding said anode from the grid and having perforations therethrough in the region of the grid perforations.

4. An electron tube comprising a vacuum envelope filled with low pressure gas and having therein a cylindrical anode, an emitting cathode, and a grid cylinder lying between cathode and anode which has perforations therein opposing the anode and both ends of which terminate at the vacuum envelope.

5. An electron tube comprising a vacuum envelope filled with low pressure gas and having therein a cylindrical anode, an emitting cathode, and a grid cylinder lying between the cathode and the anode which has perforations therein opposing the anode, said grid cylinder being affixed at one end to the vacuum wall and making sliding contact with vacuum wall at the opposite end.

6. An electron tube comprising a vacuum envelope filled with low pressure gas and having therein a cylindrical anode supported by the envelope side walls, an emitting cathode, and a grid cylinder lying between the cathode and the

anode which has perforations therein opposing the anode, said cylinder being affixed at one end to the vacuum wall and making sliding contact with vacuum wall at the opposite end.

7. An electron tube comprising a vacuum envelope filled with low pressure gas and having therein a cylindrical anode supported by a highly conductive annular member penetrating the envelope side walls, an emitting cathode, and a grid cylinder lying between the cathode and the anode which has perforations therein opposing the anode, said cylinder being affixed at one end to the vacuum wall and making sliding contact with the vacuum wall at the opposite end.

8. An electron tube comprising a vacuum envelope filled with low pressure gas and having therein a cylindrical anode supported by the envelope side walls, an emitting cathode, and a grid cylinder lying between the cathode and the anode which has perforations therein opposing the anode, said cylinder being affixed at one end to the vacuum wall and making sliding contact with the vacuum wall at the opposite end, the side walls of said vacuum envelope consisting of tubular insulators, said insulators having a spacing to the grid cylinder approximately the same as the grid-anode spacing in the regions closely adjacent the anode.

9. An electron tube comprising a vacuum envelope filled with low pressure gas and having therein a cylindrical anode supported by the envelope side walls, an emitting cathode, and a grid cylinder between cathode and anode which cylinder has a low heat flow impedance portion at one end, perforations through an adjacent portion of the cylinder opposing the active anode and resilient contact means at the other end of the cylinder, the side walls of said vacuum envelope consisting of tubular insulators, said insulators having a spacing to the grid cylinder approximately the same as the grid-anode spacing and tubular metallic members sealed to said insulators at both ends of the tube, one of said members being in turn sealed to the low heat flow impedance portion of the grid cylinder and the other member furnishing a contact surface for the resilient contact means at the other end of the grid cylinder.

10. An electron tube comprising a cylindrical anode supported by a highly conductive annular member penetrating the vacuum envelope side walls, an emitting cathode, a grid cylinder between cathode and anode which cylinder has a low heat flow impedance portion at one end, perforations through an adjacent portion of the cylinder opposing the active anode and resilient contact means at the other end of the cylinder, a vacuum envelope enclosing said elements filled with low pressure gas and consisting of side walls composed of tubular insulators, said insulators having a spacing to the grid cylinder approximately the same as the grid-anode spacing, tubular metallic members sealed to said insulators at both ends of the tube, one of the said members being in turn sealed to the low heat flow impedance portion of the grid cylinder and the other member furnishing a contact surface for the resilient contact means at the other end of the grid cylinder, a vacuum closure sealed within the grid wall between the perforated region of the grid and the end of the cylinder sealed to the envelope side walls, and closure means including the cathode assembly sealed to the opposite end of the envelope side walls.

11. An electron tube comprising a vacuum

envelope filled with low pressure gas and having therein an anode, a grid cylinder having a perforated region opposing the anode, and an integral cathode assembly consisting of a tubular

5 cathode to which emitter is applied, sealing means between the cathode and a grid-potential tubular member including a dielectric ring, said dielectric ring being close spaced at all points to metallic members, sealing means including a 10 dielectric ring closing the end of the cathode cylinder, and heater means within said cathode.

12. An electron tube comprising a vacuum envelope filled with low pressure gas and having therein an anode, a grid cylinder having a per-

15 forated region opposing the anode, and an integral cathode assembly consisting of a tubular cathode to which emitter is applied, sealing means between the cathode and a grid potential tubular member including a dielectric ring, said 20 dielectric ring being close spaced at all points to a metallic member, sealing means including a dielectric ring closing the end of the cathode cylinder, and heater means within said cathode consisting of a high inductance filament axially

25 disposed and connected at one end to the cathode cylinder and at the other end to a lead coaxial with the cathode cylinder which lead penetrates the sealing means closing the end of the cathode cylinder.

30 13. An electron tube comprising a vacuum envelope filled with low pressure gas and having therein an anode, a grid cylinder having a perforated active grid opposing the anode, and an integral cathode assembly consisting of a tubular

35 cathode to which emitter is applied, an axially disposed baffle located at and serving to partially close the end of the cathode cylinder internal of the tube to which end said baffle is connected, sealing means between the cathode and the grid 40 cylinder including a dielectric ring, said dielectric ring being close spaced at all points to a metallic tube member, sealing means including a dielectric ring closing the end of the cathode cylinder, and heater means within said cathode consisting of

45 a helically wound filament coaxially disposed within the cathode and connected at one end to the cathode baffle and at the other end to a lead coaxial with the cathode cylinder which lead penetrates the sealing means closing the end of the 50 cathode cylinder.

14. An electron tube comprising a vacuum envelope filled with low pressure gas and having therein an anode, a grid cylinder having a per-

55 forated active grid opposing the anode, and an integral cathode assembly consisting of a tubular cathode to which emitter is applied, sealing means between the cathode and the grid cylinder including a dielectric ring, said dielectric ring being close spaced at all points to a grid

60 potential member, sealing means including a dielectric ring closing the end of the cathode cylinder, and heater means within said cathode.

15. An electron tube comprising a vacuum envelope filled with low pressure gas and having therein an anode, a grid cylinder having a per-

65 forated active grid opposing the anode, and an integral cathode assembly consisting of a tubular cathode to which emitter is applied, sealing means between the cathode and the grid cylinder including a dielectric ring, said dielectric ring being close spaced at all points to a grid potential cylinder, sealing means including a dielectric ring closing the end of the cathode cylinder, and heater means within said cathode consisting of

70 75 a high inductance filament axially disposed and

connected at one end to the cathode cylinder and at the other end to a lead coaxial with the cathode cylinder which lead penetrates the sealing means closing the end of the cathode cylinder.

16. An electron tube comprising a vacuum envelope filled with low pressure gas and having therein an anode, a grid cylinder having a perforated active grid opposing the anode, and an integral cathode assembly consisting of a tubular cathode to which emitter is applied, sealing means between the cathode and the grid cylinder including a dielectric ring sealed at both edges to metallic sleeves, said dielectric ring being close spaced at all points to a grid potential cylinder, sealing means including a dielectric ring closing the end of the cathode cylinder, and heater means within said cathode.

17. An electron tube comprising a vacuum envelope filled with low pressure gas and having therein an anode, a grid cylinder having a perforated active grid opposing the anode, and an integral cathode assembly consisting of a tubular cathode to which emitter is applied, an axially disposed baffle located at and serving to partially close that end of the cathode cylinder internal of the tube, sealing means between the cathode and the grid cylinder including a dielectric ring sealed at both edges to metallic sleeves said dielectric ring being close spaced at all points to a grid potential cylinder, sealing means including a dielectric ring closing the end of the cathode cylinder, heater means within said cathode consisting of a helically wound filament axially disposed and connected at one end to the axially disposed baffle and at the other end to a lead coaxial with the cathode cylinder which lead penetrates the sealing means closing the end of the cathode cylinder.

18. An electron tube comprising a vacuum envelope filled with low pressure gas and having therein an anode, an emitting cathode, a grid wall between the anode and the cathode which has perforations therein opposing the active anode and baffle means so positioned between cathode and grid, close to the grid, that it permits equal path lengths between cathode and anode through each grid perforation.

19. An electron tube comprising a vacuum envelope filled with low pressure gas and having therein an anode, an emitting cathode, a grid wall between the anode and the cathode which has perforations therein opposing the active anode and baffle means between cathode and grid, close to the grid, said baffle means terminating at equal distances from their respective perforations.

20. An electron tube comprising a vacuum envelope filled with low pressure gas and having therein an anode, an emitting cathode, a grid wall between the anode and the cathode which has perforations therein opposing the active anode and baffle means between cathode and grid in front of and close to the grid perforations, said means terminating at equal distances from their respective perforations, so that the current paths between cathode and anode through all of the perforations are essentially the same length.

21. An electron tube comprising a vacuum envelope filled with low pressure gas and having therein an anode, an emitting cathode, a grid wall between the anode and the cathode which has perforations therein opposing the active anode, and baffle means between cathode and grid in front of each perforation, said means being supported by the grid adjacent each perforation.

22. An electron tube comprising a vacuum envelope filled with low pressure gas and having therein a cylindrical anode, an emitting cathode, a cylindrical grid wall between anode and cathode which has perforations therein opposing the active anode, and baffle means between cathode and grid in front of each perforation, said means being supported adjacent each perforation.

23. An electron tube comprising a vacuum envelope filled with low pressure gas and having therein a cylindrical anode, an emitting cathode, a cylindrical grid wall between anode and cathode which has perforations therein opposing the active anode, and a cylindrical baffle coaxially located within the grid in front of the perforations.

24. An electron tube comprising a vacuum envelope filled with low pressure gas and having therein a cylindrical anode, an emitting cathode, a cylindrical grid wall between anode and cathode which has perforations therein opposing the active anode, and individual baffle means in front of each perforation supported by the grid adjacent each perforation.

25. An electron tube comprising a vacuum envelope filled with low pressure gas and having therein an anode, an emitting cathode, a grid wall between the anode and the cathode which has perforations therein opposing the active anode, and metallic deionization vanes affixed to portions of the grid and cathode extending into the region between the cathode and the grid.

26. An electron tube comprising a vacuum envelope filled with low pressure gas and having therein a cylindrical anode, an emitting cathode, a cylindrical grid wall between the anode and the cathode which has perforations therein opposing the active anode, and metallic deionization vanes affixed to a grid potential surface and extending into the grid-cathode region.

27. An electron tube comprising a vacuum envelope filled with low pressure gas and having therein a cylindrical anode, an emitting cathode, a cylindrical grid wall between the anode and the cathode which has perforations therein opposing the active anode, and metallic deionization vanes affixed to the grid in the region of perforation and extending tortuously toward the tube axis.

28. An electron tube comprising a vacuum envelope filled with low pressure gas and having therein a cylindrical anode, an emitting cathode, a cylindrical grid wall between the anode and the cathode which has perforations therein opposing the active anode, and deionization vanes which also serve as baffle means consisting of metallic members affixed to the grid in the region of perforation so that they partially block the perforations and extend tortuously toward the tube axis.

29. An electron tube comprising a vacuum envelope filled with low pressure gas and having therein a cylindrical anode, an emitting cathode, a grid cylinder lying between cathode and anode which has perforations therein opposing the active anode and both ends of which terminate at the vacuum envelope, and a tubular coaxial auxiliary electrode between grid and anode having perforations therethrough.

30. An electron tube comprising a vacuum envelope filled with low pressure gas and having therein a cylindrical anode supported by the envelope side walls, an emitting cathode, a grid cylinder lying between the cathode and anode which has perforations therein opposing the ac-

tive anode, said cylinder being affixed at one end to the vacuum wall and making sliding contact with the vacuum wall at the opposite end, and a tubular coaxial electrode between grid and anode having perforations therethrough, said electrode being supported by the envelope side walls.

31. An electron tube comprising a vacuum envelope filled with low pressure gas and having therein a cylindrical anode supported by the envelope side walls, an emitting cathode, a grid cylinder lying between the cathode and anode which has perforations therein opposing the active anode, said cylinder being affixed at one end to the vacuum wall and making sliding contact with the vacuum wall at the opposite end, and a tubular coaxial electrode between grid and anode having perforations therethrough, said electrode being supported by the envelope side walls by means affixed near one end thereof, the other end of the electrode extending below the adjacent surrounding electrode thereby shielding said surrounding electrode from the adjacent surrounded electrode and from all elements which said surrounding electrode surrounds.

32. An electron tube comprising a vacuum envelope filled with low pressure gas, the envelope side walls being a metallic grid cylinder, an anode supported by one end wall, an emitting cathode supported by the other end wall, and a perforated grid-potential member lying between said anode and said cathode.

33. An electron tube comprising a vacuum envelope filled with low pressure gas, the envelope side walls being a metallic grid cylinder, a planar anode supported by one end wall, an emitting cathode supported by the other end wall, and grid potential members surrounding said anode, that portion of said members between the cathode and grid having perforation therethrough.

34. An electron tube comprising a vacuum envelope filled with low pressure gas, the envelope side walls being a metallic grid cylinder, a planar anode extended radially from an axial support which is sealed through one end wall, a tubular emitting cathode assembly forming the closure at the other end of the tube sealed to the grid cylinder by means including a dielectric ring which is close spaced to the grid cylinder, and planar grid potential members on both sides of the anode, that member between cathode and anode being perforated and that on the other side being annular and having an inner edge which terminates on an extension of the dielectric portion of the end wall.

35. An electron tube comprising a vacuum envelope filled with low pressure gas, the envelope side walls being a metallic grid cylinder, a planar anode extending radially from an axial support which is sealed through one end wall, a tubular emitting cathode assembly forming the closure at the other end of the tube sealed to the grid cylinder by means including a dielectric ring which is close spaced to the grid cylinder and including a high impedance heater filament disposed coaxially within the cathode, planar grid potential members on both sides of the anode, that member between cathode and anode being perforated and that on the other side being annular, its inner edge terminated on an extension of the dielectric portion of the end wall and baffle means disposed in front of each of the grid perforations, and supported by means adjacent each perforation.
